UNITED STATES PATENT OFFICE

SYDNEY S. SMITH, OF TULSA, OKLAHOMA, ASSIGNOR TO SHELL PETROLEUM CORPORATION, A CORPORATION OF VIRGINIA

RECTIFIER

Application filed March 29, 1930. Serial No. 439,883.

This invention relates to the art of distillation and more particularly to apparatus for fractionally distilling by rectification composite liquids comprising components having different boiling points.

The embodiment of the invention particularly described is adapted for the rectification of hydrocarbon mixtures such as natural gas gasoline or refinery gas condensates, but it should be understood that the process has wider uses and is not limited, therefore, to refining of petroleum products.

A more specific object of the invention is to provide apparatus for effecting a sharp cut between the fractions of a liquid which includes volatile fractions having different boiling points, whereby a separation of the various fractions may be made, and selected products withdrawn in substantially a pure state.

The general object of the invention is to provide apparatus for continuous fractional distillation of volatile liquids which is accurate, efficient, economical in operation and simple to control.

Fig. 1 is a side view of the apparatus partly diagrammatical.

Fig. 2 is a detail drawing partly in section of the upper part of the apparatus including the condenser.

Fig. 3 is a detail view partly in section of the lower part of the apparatus including the kettle.

Fig. 4 is a cross-section through either the condenser or the kettle on line 4—4, Fig. 2, or Fig. 3.

Fig. 5 is a detail view of a plate showing the core construction.

Fig. 6 is a cross-section through a plate on line 6—6, Fig. 5.

The apparatus comprises generally a series of horizontal cylindrical plates arranged in a vertical plane; a kettle at the bottom; a condenser at the top; a number of series of vertical connections between the kettle, plates and condenser, each series of connections being arranged in a vertical line and arranged to permit from any section of a plate downward flow only in the liquid phase, and horizontal and upward flow in

the vapor phase; means for introducing the input on a series of plates at one end; means for withdrawing the liquid component at the bottom, the final end vapor component at the top, and intermediate components in the vapor phase at intermediate plates, the withdrawal taking place at the end opposite the end receiving the input; and means for automatically regulating the temperatures by controlling the flow of the heating fluid through the kettle and the cooling fluid through the condenser.

The plate assembly comprises a series of condenser plates 1 in the form of cylindrical tubes each horizontally disposed and arranged in a vertical plane and equally spaced one from the other. The kettle 2 is mounted at the bottom and a condenser 3 is mounted at the top of the plate assembly. The kettle, plates and condenser are connected by a number of series of vertical tubes 4, each of the tubes in a series being in vertical alignment. The tubes 4 may be attached to the plates 1, the kettle 2 and the condenser 3 by welding.

The left end of the apparatus may for convenience be designated the receiving side and the right end the delivery side.

Each of the plates 1 has at the receiving side a reducer head 6 in which may be fitted a plug 7 or a valve 8. On the delivery side it may be provided with a valve 9 for withdrawal of a component in the vapor phase either for purpose of sampling, or condensation and storage. Each plate 1 has a core in order to increase the contact surface and such a core may be constructed of a tight roll of expanded metal lath 11 wrapped with hardware cloth 12.

The kettle 2 includes a shell 13 to which is attached the vertical tubes or risers 4. A series of tubes 14 are situated within the shell 13 and are connected at each end to a header plate 15, thus providing manifold chambers 16 and 17. A connection 18 leads into the chamber 16 providing communication for the introduction of steam and the condensate is withdrawn through the chamber 17 by a connection 19. A connection 20 is provided

in the delivery side of the kettle for the withdrawal of the final liquid component.

The condenser 3 is constructed in a manner similar to the construction of the kettle. A shell 21 is connected by the tubes 4 to the plate assembly. A series of horizontal tubes 22 are connected at each end to a header plate 23 providing chambers 24 and 25. A connection 26 is made with the chamber 24 for the introduction of a cooling fluid such as water and a connection 27 is made with the chamber 25 for the withdrawal of the spent fluid. A connection 28 is made with the shell 21 for the withdrawal of the final end vapor component and a manually controlled valve 29 may be interposed in a pipe leading from the connection 28 for the control of the flow of the end vapor component. A safety pressure valve 30 in communication with the connection 28 may be ordinarily used for the discharge of the vapor component.

A manifold 32 is connected to a series of plates 1 through the valves 8 and has connected to it a pipe 33 to receive the input.

Intermediate vapor components may be taken off of any one of the plates 1 through its valve 9 and a pipe 34 leading to a condenser coil 35.

A tube 36 may be connected to any of the plates 1 and leads to a temperature recorder or indicator 37.

The temperature and the operation of the rectifier may be controlled by automatically regulating the flow of steam through the kettle and the flow of water through the condenser. The steam regulating mechanism may comprise a tube 38 connected to a plate 1, a thermostat, 39 and a steam valve 40 in the pipe 18. The water regulating mechanism may comprise a pipe 41 leading from a plate 1, a thermostat 42, and a valve 43 between a water supply pipe 44 and the connection 26.

The feed may be entered on the receiving side through the manifold 32 to a series of plates 1. A liquid level is maintained within the kettle at a height sufficient to give complete submergence of the tubes 14 in the liquid. This control may be accomplished manually or by a float control, not shown, but which may be of a type well known in the industry. The pressure may be controlled by vapor removal through the pressure valve 30 or manual valve 29. Temperatures at the condenser and kettle may be controlled by the thermostatic apparatus illustrated and described.

The principle of operation of this rectifier may be explained by comparison with other types of rectifying columns. In the operation of a continuous process column, the temperature gradient and the composition gradient are distorted by the throughput or take-off of the components; and the action of the column and the accuracy of separation between individual components is quite differ-

ent when the column is shut in and no component is being removed, from conditions when there is a throughput. The accurate fractionation obtained while a column is shut in is obtained by the infinite reflux.

By apparatus constructed in accordance with this invention, results approaching in accuracy those inherent in a shut-in column, are obtained together with the advantages inherent in a continuous flow rectifier.

It will be observed that the vertical tubes 4 in reality comprise a number of vertical columns, nineteen as illustrated, while the plates, including the kettle and the condenser, number thirty. For convenience of description I may number these columns from left to right; or from the receiving side, one to nineteen; and the plates from bottom to top, one to thirty.

For example, as illustrating the operation of the device, it may be assumed that it is desired to operate the rectifier as a stabilizer for natural gasoline being fed to plates ten to eighteen, adjacent column one; and that end products are to be taken off adjacent column nineteen, propane at plate thirty, butane at plate twenty-three, and the residue at plate one, as shown in the drawings. A molecule of butane introduced adjacent column one on plates ten to eighteen traverses a tortuous course, moving in its liquid phase downward in any of the several columns and in its vapor phase upward and horizontal. The construction and operation of the apparatus will be such as to confine it at column nineteen between the eighteenth and twenty-eighth plate. The molecule will during its tortuous course tend to confine itself between those plates. At or about the twelfth column the individual components will be roughly separated but not with such accuracy as to confine the molecule of butane within the selected plates. Its range of movement between the plates will be progressively decreased until it reaches the nineteenth plate where it may be taken off accurately at the twenty-third plate.

It is to be understood that the foregoing discussion is merely illustrative of the theory of operation. Butane, a single hydrocarbon, has been selected as an illustration of an intermediate fraction merely for simplicity of explanation, but such a cut would ordinarily include a group of hydrocarbons having a limited boiling range rather than a single compound. The operation of the apparatus has been described hypothetically in connection with the rectification of natural gasoline. By comparison, were the apparatus used to distill relatively heavy oil, for instance, gasoline and the lighter fractions might be taken off as a final end vapor product, kerosene as an intermediate product in its vapor phase after it has traversed a course similar to that just described in connection with butane in

the other illustration, and the residue would be taken off as a final liquid product.

It is also to be understood that the number of columns and number of plates is not limited as specifically illustrated and described, but either may vary within wide limits depending upon the intended input and the separations desired.

It will thus be seen that a rectifier has been provided whose temperature gradient and composition gradient is affected but little in its final operation by the throughput and whose accuracy approaches that of a shut-in column. At the same time the apparatus compares favorably in cost of construction and operation with less accurate continuous rectifiers.

While the device has been illustrated and described as applicable to the stabilization of petroleum products, its application may be extended to a wide range of uses with accuracy of results and economy in construction and operation.

It is obvious that various changes in construction may be made within the scope of the appended claims without departing from the spirit of this invention.

I claim:

1. A rectifier including a series of vertical tubes in lateral alignment, a series of superimposed horizontal tubes each of which is in communication with said vertical tubes, means for maintaining a temperature gradient in said horizontal tubes, a connection for introducing input into one or more horizontal tubes adjacent a vertical tube, and connections for withdrawing the end products adjacent a vertical tube remote from the input.

2. A rectifier including a series of superimposed horizontal tubes, a vertical tube adjacent the input connection, a vertical tube adjacent the connection for removal of the end products and remote from the first vertical tube, a series of vertical tubes interposed between and in lateral alignment with the two first mentioned vertical tubes, all of said vertical tubes being in communication with said horizontal tubes, and means for maintaining a temperature gradient in said horizontal tubes.

3. A rectifier including a series of superimposed horizontal tubes, a series of vertical tubes in lateral alignment connecting said horizontal tubes, a connection for introducing the input into a set of said horizontal tubes, connections for withdrawing the end products adjacent a vertical tube remote from the input connection, and means for maintaining a temperature gradient in said horizontal tubes.

4. A rectifier including a series of superimposed horizontal tubes, a series of vertical tubes in lateral alignment, each of said vertical tubes comprising pipe fittings in verti-

cal alignment and connecting into said horizontal tubes, means for introducing an input, means for taking off the final end product, and means for maintaining a temperature gradient in the horizontal tubes.

5. A rectifier including a series of superimposed horizontal tubes, a series of vertical tubes in lateral alignment connecting said horizontal tubes, and means for maintaining a temperature gradient including a kettle connected to and at the bottom of the vertical tubes and a condenser connected to and at the top of the vertical tubes.

6. A rectifier including a series of superimposed horizontal tubes, a series of vertical tubes in lateral alignment connecting said horizontal tubes, a kettle having a shell connected to and at the bottom of the vertical tubes, and a heat exchanger within the shell.

7. A rectifier including a series of superimposed horizontal tubes, a series of vertical tubes in lateral alignment connecting said horizontal tubes, a condenser having a shell connected to the top of the vertical tubes, and a heat exchanger within the shell.

8. A rectifier including a series of horizontal tubes, a condenser having a heat exchanger, a kettle having a heat exchanger, said horizontal tubes, condenser and kettle being arranged in vertical alignment, a series of vertical tubes in lateral alignment connecting said horizontal tubes, condenser and kettle, and automatic means for regulating the flow of thermal fluids through the heat exchangers of the condenser and kettle.

9. In a rectifier a series of superimposed horizontal tubes arranged to perform the function of plates, each of said tubes having a tight roll of metal lath or its equivalent within the tube.

10. A rectifier having a series of horizontal tubes in vertical alignment, a condenser above the tubes, a kettle below the tubes, a series of vertical tubes connecting the horizontal tubes, condenser and kettle, a manifold connected to one end of selected horizontal tubes, and connections near the other end vapor component at the condenser and the final liquid component at the kettle.

11. A rectifier including a series of superimposed horizontal tubular members, a series of vertical tubes arranged in lateral alignment and connecting the horizontal tubes, means for maintaining a temperature gradient in the horizontal tubes, a connection to introduce the input at one end of the horizontal tubes, and connections to one of the horizontal tubes at the other end to withdraw an intermediate component in the vapor phase.

12. A rectifier including a series of superimposed horizontal tubes each packed with a roll of metal lath, or its equivalent, to increase the surface exposure, a heat exchanger above the horizontal tubes, a heat exchanger below the horizontal tubes, a plurality of con-

nections between each set of adjacent tubes and between the heat exchangers and the tubes adjacent thereto, an input manifold at one end of the tubes, and connections on the end opposite said manifold for withdrawing the end products.
